UNITED STATES PATENT OFFICE.

LOUIS DIAMOND, OF NEW YORK, N. Y.

TRUNK.

Application filed April 1, 1924. Serial No 703,337.

To all whom it may concern:

Be it known that I, LOUIS DIAMOND, a citizen of the United States of America, residing at New York city, county and State 5 of New York, have invented certain new and useful Improvements in Trunks, of which the following is a specification.

This invention relates to trunks and cases and in particular to certain features of construction which make a trunk or case more durable and lasting.

A particular object of the invention is to provide a construction wherein the corners of the trunk may be made rounded and reinforced at that point, as the dropping of a trunk causes greatest wear at the corners thereof.

A further object is to provide a trunk, the body of which may be made up of three 20 or four parts, depending upon the type of trunk desired and strength required.

A further object is to provide an outer casing for a trunk frame or body which can be made up of three parts, separately and 25 the parts assembled to the trunk body to complete the finished article.

Referring to the drawings wherein I have shown a preferred embodiment of my invention;

30 Figure 1 is a view in perspective of a trunk embodying my improved features of construction;

Figure 2 is a section on the line 2—2 of Figure 1;

35 Figure 3 is a section on the line 3—3 of Figure 1;

Figure 4 is an enlarged sectional view of the corner of a trunk showing a portion also of the interior frame of the trunk;

40 Figure 5 is a view in perspective showing the inside frame of the trunk with its protective covering, the end of the covering being shown removed and in a position to be applied to the end of the trunk;

45 Figure 6 is an enlarged section taken on the line 6—6 of Figure 5; and,

Figure 7 is an enlarged section taken on the line 7—7 of Figure 5.

50 Referring to the drawing in detail 5 indicates a trunk body having the usual lid or cover 6, the latter of which is attached to the trunk body through the medium of the usual hinges 7.

55 The trunk body and cover are usually made up of an inner frame of heavy wood and an outer covering of fiber or other ma-

terial, and the time and expense incurred in applying this covering greatly adds to the cost of the finished trunk. Also the coverings in use are unsatisfactory inasmuch as they must be bound on the outer sides of the edges with a reinforcing strip which becomes battered and roughened so that the trunk soon presents an unsightly appearance and is a menace to the handlers thereof.

60 My improved construction eliminates the outside reinforcement and also saves time and labor in the application of the covering to the body of the trunk.

65 The covering is made up of an outer layer of heavy fiber 8 and an inner layer 9 of thin wood such as cedar. The bent corners are reinforced as by the strips 10 of sheet iron which are disposed one between the fiber 8 and the wood 9 and the other on the inside 70 of the wood 9 so that both edges of the bottom of the trunk, and both edges of the top of the trunk cover will be reinforced by these strips 10. The cover 6 is, of course, 75 constructed the same as the trunk body. 5. 80 These strips are nailed or otherwise suitably held in place by fastening from the inside. The covering may of course be made heavier and could serve as the trunk body, but I prefer to use a heavy wood frame 11 85 around which the covering is placed.

85 The ends of this frame 11 are covered by end pieces 12 which as shown in Figures 5, 6 and 7 are made up of an outer layer of fiber 8 and inner layer of wood 9 to match 90 the covering of the body of the trunk and at the junction of its extended portions 13, 14, and 15 with the main portion 16, it is reinforced by the usual metal strips 10, so that when the main portion 16 is placed on the end 17 of the inner frame 11 and the extended portions 13, 14 and 15 bent over to meet the main covering, at which point the two are joined by a strip 18 on the exterior of the trunk. The meeting points 95 of the extensions are also joined by a like strip. Therefore, the frame 11 is completely covered by a covering comprising 3 pieces as is also the lid or cover of the trunk.

100 This covering provides a cushion effect and also round edges on the trunk. Also, it does away with edge reinforcing in the nature of outer strips which after long handling, will become jagged and present an unsightly appearance and be a menace to the 110 handlers of the trunk.

The inner frame may of course be fas-

tened as by nails or other suitable means to the covering, although it is intended that this covering will have a very tight fit over the frame, and when assembled the frame 5 and its covering will be substantially integral.

It will be seen therefore that I have provided a trunk in which the amount of nails used will be reduced to a minimum, the 10 labor of assembling will be reduced, and the amount of time consumed in completing the trunk will be reduced to a minimum and the cost of the trunk accordingly reduced.

Having described my invention, what I 15 claim is:—

1. A trunk comprising a frame, a cover for said frame, said cover comprising a center portion and end pieces having extended portions, and means for fastening the end 20 extended portions to the center portion.

2. A trunk comprising a frame, end covering pieces for said frame, a centrally disposed covering for said frame, said central covering consisting of a plurality of continuous layers of material, and transversely 25 disposed reinforcing members between said layers at the point in said covering where the same is bent around said frame.

3. A trunk comprising a body and a lid portion, the mid-sections and ends of the 30 body and lid portions being surrounded by a covering having a central portion and end portions, said covering made up of a layer of fibre and a layer of thin wood, and transversely disposed metallic reinforcing bands 35 between the fibre and the wood of the covering where the same bends around said body and lid portion.

LOUIS DIAMOND.
